UNITED STATES PATENT OFFICE.

WALTER M. INGRAM, OF BALTIMORE, MARYLAND, ASSIGNOR TO THE RELIANCE PUMP AND MACHINE COMPANY, OF BALTIMORE, MARYLAND, A CORPORATION OF MARYLAND.

TIRE PUMP.

Application filed December 4, 1922. Serial No. 604,713.

The invention relates to a pump which in the form shown is manually actuated, for compressing air. It is commonly used for the inflation of automobile and bicycle 5 tires and the like. In such pumps, the valves are one of the principal sources of difficulty with and failure of the apparatus, and while compounding is necessary to give the requisite quick action, increasing the number of 10 valves on this account increases the difficulty incident to their operation. Likewise there is increased resistance incident to the passage of air through the valves. The object of the present invention is to overcome these 15 difficulties, producing a valveless compound pump of slight resistance, long life and compact arrangement.

In the form shown, the low pressure cylinder is of annular cross section, the high 20 pressure cylinder occupying the center of the annulus, the axis of the two being coincident, the two cylinders as shown are upright, the intake to the high pressure cylinder, or as it is termed herein, the transfer 25 port from the low to the high pressure cylinder being preferably near the base. In the form shown, the latter cylinder is raised slightly from the base for this purpose, i. e. to provide such a port or passage between 30 the base and the bottom edge of the high pressure cylinder. The intake to the low pressure cylinder is at the top, as around the piston rods which are without packing for this purpose. The delivery is likewise 35 at the top. The pistons, the outer or lower pressure being of annular form and actuated by two or more rods are packed by cup washers, the low pressure piston being packed by a double cup or double flanged 40 ring so that the air passes the pistons in one direction, but not in the other.

In short, the cylinders are concentric one within the other, the intake and delivery being at one end and the transfer port at 45 the other and the edges of the packing cups are turned in the direction in which the air is compressed, i. e. the low pressure packing toward the transfer port and the high pressure toward delivery.

50 On the down stroke, air is drawn into the low pressure cylinder and on the up stroke it passes the low pressure piston being drawn into the high pressure cylinder by the up stroke of the piston in that cylinder, it being

understood that the pistons in the two cylinders move together, being connected to a single grip or handle by three piston rods. At the same time that the air is being drawn into one end of the high pressure cylinder as aforesaid, the air above the piston is being 55 compressed and forced outward through the delivery opening which is at the top. On the down stroke, the high pressure piston permits the air which was drawn in beneath it to pass the piston and the low pressure 60 piston on its up stroke permits the air which has entered above it to pass into the space beneath the pistons ready to be transferred 65 to the high pressure cylinder on the next down stroke.

70 In the accompanying drawings, I have illustrated a pump constructed in accordance with my invention. In the drawings:

Figure 1 is a vertical central section.

Fig. 2 is a section of the top portion of 75 the cylinders also on a vertical plane at right angles to the section of Fig. 1, the same being on the line 2-2 of Fig. 3.

Fig. 3 is a section taken through the piston rods 3-3 of Fig. 1, looking downward 80 at the top of the cylinders.

Fig. 4 is a section on the line 4-4 of Fig. 1, looking downward at the pistons and at the base.

Fig. 5 is a vertical central section and 85

Fig. 6 is a section on line 6-6 of Fig. 7, of a modified form of the pump, showing the cap fastening.

Fig. 7 is an elevation of the top portion 90 of the cylinder, and Fig. 8 shows the inside of the cup.

Referring to the drawings by numerals, the pump as shown consists of an outer cylindrical casing 1, flanged at the bottom at 2, and secured to the base 4, as hereinafter 95 described. The outer cylindrical casing 1, has an inwardly inclined taper, i. e. a frusto conical portion 6, at the top which terminates in a cylindrical neck 7, of smaller diameter than the outer casing 1. As shown 100 it is approximately half the diameter of the outer cylinder. In this neck there is secured in any suitable manner a tubular member or inner cylinder 8, which fits tightly within the neck 7, and may be held by soldering 105 or brazing or by merely being forced into the neck opening.

The inner cylinder forms the high pres-

sure cylinder of the pump. As shown, its lower end is spaced slightly upward from the base 4, forming a transfer port 13, connecting the high and low pressure cylinder.

5 The outer casing 1, or rather the space between the outer casing and inner or high pressure cylinder 8, forms the low pressure cylinder. The upper end of the high pressure cylinder 8 is closed by a plug 9 which is 10 apertured at 10, centrally, and in alignment with the axis of the cylinder to admit the high pressure piston rod 11. The extreme upper end of the cylinder 8 is threaded at 12, to engage a packing nut 14, and suitable 15 packing 15, shown in the form of a washer is clamped between the nut 14 and the plug 9, the latter having a packing chamber 16, formed by enlarging the upper end of the annular opening 10 therein. The packing 20 in the form of a centrally cupped soft washer is placed on the plug 9, and the nut 14, is screwed down thereon, or any suitable packing may be used.

25 In the high pressure cylinder is a piston packed with a cup washer, the same being sufficiently loose to pass the air on the down stroke, offering by means of the usual cup packing action sufficient resistance to its passage on the up stroke to hold the air and to 30 compress it, forcing it through the delivery opening, which as shown is supplied with a suitable fitting in the nature of a hose connection 18. The piston as shown consists 35 of a concave disc 19, secured to the piston rod 11, near the end, and a removable nut 20, which engages the rod and holds the cup washer 21 which is of the ordinary type centrally apertured and bent upward around the disc 19, so that its edges lie flat against 40 the cylinder walls extending in the direction of delivery, the washer being between the disc and the nut 20. The low pressure piston as 45 shown consists of a ring or annulus 22, which fits loosely within the annular low pressure space 23, between the outer casing 1, and the inner cylinder 8. This is secured by riveting or otherwise to two or more piston rods 24, which extend upward through apertures 25, in the conical portion 6 at the top of the cylinder, these openings as aforesaid being sufficiently free to provide an air intake 50 opening for that purpose. An annular cup washer 26, having its two respective circular edges turned downward into contact with the inner walls of the outer casing 1, and the inner walls of the inner cylinder 8, is held in position on the bottom face of 55 the ring 22, by a second ring 27, which may be riveted or otherwise secured to the ring 22, the washer being between the rings.

60 Important points are that the cylinders are concentric, one enclosing the other and the cup packings have their edges turned in opposite directions, i. e. the washer in the high pressure cylinder has its edges turned to-

ward delivery and the washer in the low pressure cylinder has its edges turned toward the transfer port and no valves are necessary.

65 The three piston rods 24, 24 and 11 are 70 parallel and preferably in line transversely so that they may to advantage be all three of them secured to a transverse handle or grip 30, being to advantage as shown shouldered at 31 near the upper ends. The end portions 32 pass through the handle and are held by the nuts 33, suitable washers being provided at both sides of the handle to be engaged by the shoulders at one end and the nuts at the other. The base flange 2, of the 75 outer cylinder may be packed by means of a suitable gasket 34, and held from above by the cast iron base ring 35, the same having ears 36 at opposite sides which are slotted at 80 37 to receive the base bolts 38.

85 In Figures 5, 6, and 7, I have shown a modified form of the invention. This form has the low pressure cylinder 34, closed at the top by a removable cap 35, which fits inside the opening of cylinder. Except for the removable feature and the taper which is non-essential, it is like the top of the low pressure cylinder of the first form.

90 The low pressure cylinder is secured to the base 36, at the bottom by spinning the bottom edge of the cylinder outward at 37, to fit a groove or expanded portion 380, of a socket 39, formed in the base for that purpose. The base is preferably bossed up at 95 40 around the socket.

100 The means for fastening the cap is peculiar, both the cap and the cylinder being provided with peripheral registering grooves 41 and 42 in the overlapping portion of these 105 respective members, the cap being preferably shouldered at 43, to position the grooves. The grooves when in registrative relation form a circumferential passage 44, of circular cross section between the members 34 and 35. Inside the cap in unfastened condition, see Fig. 8, is a wire bolt 45 of spring steel in the form of a single ring, concentric with, and lying against the inside of the cap and having both ends free, one end 46 being turned out through a slot 47, in the cap, which slot cuts out part of the groove in the cap coinciding therewith and extending in the direction of the circumference. The other end 49 is turned inward. The 110 cylinder has a slot 48 extending downward from the top edges thereof to the groove and preferably enlarged toward the top. When the cap is placed on the cylinder, the end 46, projects outward through the slot 48, in the cylinder to which slot 48, the end of the wire bolt is thus secured. As the cap is 115 turned right handed, the wire is drawn through the slot 47 in the cap into the passage between the cap and cylinder, being half in one groove and half in the other, see 120 125 130

Figs. 5 and 6. When a complete turn has been made the rotation is stopped by contact of the two ends of the wire bolt, Fig. 6, the inner end 49 being hooked over the end of the slot 47. To unlock it the cap is oppositely rotated, forcing the wire back through the slot 47, to its original position inside the cap.

I have thus described specifically and in detail a single embodiment of my invention in the preferred form in order that the nature and operation of same may be clearly understood by those skilled in the art; however, the specific terms herein are used descriptively rather than in a limiting sense, the scope of the invention being defined in the claims.

What I claim and desire to secure by Letters Patent is:

- 20 1. An air pump for inflating pneumatic tires consisting of an outer casing having a portion at the top of smaller diameter than the cylinder, a high pressure cylinder secured to said portion and extending down into the outer casing, a transfer port near the bottom of the high pressure cylinder, the space between the inner cylinder and the outer casing forming a low pressure cylinder, an annular piston having flexible pack-
25 ing edges extending downward along both walls of the low pressure cylinder, a piston in the high pressure cylinder having flexible packing with oppositely disposed edges,

parallel piston rods connected to a single handle, a delivery opening near the top of the high pressure cylinder and an intake opening near the top of the low pressure cylinder.

2. In a pump the combination of two members, a cylinder and a removable cap for one end of the cylinder, the cylinder having a piston therein, and a piston rod, the cap and cylinder having projecting cylindrical edges as to which edges one member encloses the other of said members, positioning means to limit the overlap of the edges of the cap and cylinder, which edges are provided each with a groove, the two grooves registering when the parts are positioned as aforesaid providing a closed passage encircling said members, one of said members having a hole extending through the groove, the other member having a slot at an angle with the groove extending to and open at the edge of said member and a spring wire bolt of circular form, one end projecting outward through the slot when the two members are placed in cooperative relation and when the members are rotated the bolt is caused to occupy the passage between the two members locking them in closed position substantially as described.

Signed by me at Baltimore, Maryland, this 1st day of December, 1922.

WALTER M. INGRAM.
